UNITED STATES PATENT OFFICE.

HENRY M. WATCHORN, OF SAPULPA, OKLAHOMA.

TUNNELING DEVICE.

Application filed March 1, 1926. Serial No. 91,513.

My invention relates to improvements in tunneling devices, and it consists in the combinations, constructions, and arrangements herein described and claimed.

5 An object of my invention is to provide a tunneling device which will bore a hole under a street from one side to the other, and at any desired depth without the necessity of destroying any portion of the street.

10 A further object of my invention is to provide a device of the type described in which the boring mechanism and the power mechanism are simultaneously moved forward.

15 A further object of my invention is to provide a device of the type described which is durable and efficient for the purpose intended.

20 Other objects and advantages will appear in the following specification, and the novel features of the invention will be particularly pointed out in the appended claims.

25 My invention is illustrated in the accompanying drawings, forming part of this application, in which

Figure 1 is a plan view of the device shown in operation,

Figure 2 is a section along the line 2—2 of Figure 1, and

30 Figure 3 is a front elevation of the boring device.

Figure 4 is a detail view on the line 4—4 of Fig. 1.

35 In carrying out my invention, I provide a boring device which I have indicated generally at A, a power mechanism at B for operating the boring device, and a pulling mechanism at C for simultaneously drawing the boring device and power mechanism in 40 any desired direction.

The boring device A consists of a casing 4 having an auger 5 movably disposed therein. A bit 6 is removably attached to the auger 5, and a journal 7, which serves as 45 a centering point and a support for the auger when the device is in operation, is mounted upon the bit.

The power mechanism, which is the means for operating the boring mechanism, consists of a motor 8 operatively connected to a gear 9 which rotates a shaft 10 by means of a chain 11 connecting them. A pinion 12 is mounted upon the free end of the shaft 10 and is in mesh with a beveled gear 13. The bevel gear 13 is mounted upon a

shaft 14 which is held rigid by brackets 15 suspended from a support 16. A sprocket 17 is mounted upon the shaft 14 between the brackets 15. A chain 18 is placed upon the sprocket 17 and a sprocket 19 which is rigidly mounted upon the casing 4. When the motor 8 is in operation, the chain 18 will be moved in the direction of arrows 20.

To rotate the auger 5 in a direction opposite that in which the casing is rotated, I provide a shaft 21 disposed below the shaft 10, and operatively connected thereto by gears 22 and 23, respectively. By placing a sprocket 24 upon the shaft 21 and a sprocket 25 upon the free end of the auger 5, I connect them by a chain 26. Therefore, when the power mechanism is in operation, the chain 26 will move in the direction of the arrows 27.

The boring device is spaced away from the power mechanism by adjustable braces 28, one end of each being secured to the casing 4, and the opposite end being secured to the support 16. The boring device is supported by a sled 29, which is pivotally secured to the braces 28. Rods 28' aid in securing the power mechanism to the boring device.

The pulling mechanism consists of a 75 winch 30 and a rigid beam 31 carrying a pulley 32 through which the cable 33 passes. The free end of the cable 33 is secured to the casing at 34.

80 From the foregoing description of the various parts of the device, the operation 90 thereof may be readily understood. A ditch 35 is dug at the side of the street 36 and the boring device is lowered in place, see Figure 1. The beam 31 is placed across the ditch 35 and made firm by clamps 37. The 95 winch 30 is rigidly mounted across the ditch 35 and to the rear of the boring device. The power mechanism is then put in motion, thus turning the casing in anti-clockwise direction, and the auger in a clockwise direction. The cable 33 is then slowly wound upon the winch 30 as the bit 6 cuts its way beneath the street. As the bit 6 loosens the dirt, the latter is moved by means of the auger 5 to the rear of the device and is emptied out into the ditch 35. It will be observed that the width of the bit 6 is equal to the diameter of the casing 4. Therefore, the bit 6 will cut an opening large enough 100 for the casing 4 to pass therethrough.

The purposes for rotating the casing in an opposite direction to that in which the auger is rotated are: To aid in forcing the casing through the hole as it is made, and 5 to cause the dirt to be carried back at a greater speed. After the hole has been bored, by reversing the beam 31 and the winch 30, the device may be readily removed. Any suitable power mechanism may be used, 10 such as a tractor, or a motor mounted upon a movable support.

I claim:

1. A tunneling device comprising an auger, a casing therefor, power means for 15 rotating the auger in one direction and for rotating the casing in the opposite direction, adjusting means cooperating with said power means for varying the position of said auger and said casing with respect to said 20 power means, a sled for supporting said casing and said auger, and means for simultaneously moving said casing, said auger, and said power means forwardly.
2. A tunneling device comprising an 25 auger, a casing therefor, power means for rotating the auger in one direction and for rotating the casing in the opposite direction, adjusting means cooperating with said power means for varying the position of 30 said auger and said casing with respect to said power means, a sled for supporting said casing and said auger, and means for simul-

taneously moving said casing, said auger, and said power means forwardly, said last named means returning said boring device 35 to its free position when reversed.

3. A tunneling device comprising an auger, a casing therefor, power means for rotating said auger in one direction and for rotating said casing in the opposite direction, 40 adjusting means cooperating with said power means for varying the position of said auger and said casing with respect to said power means, a sled for supporting said casing and said auger, and manually operated 45 means for simultaneously moving said casing, said auger and said power means forwardly.

4. A tunneling device comprising an auger, a casing therefor, power means for 50 rotating said auger in one direction and for rotating said casing in the opposite direction, adjusting means cooperating with said power means for varying the position of said auger and said casing with respect to said power means, a sled for supporting said casing and said auger, and manually operated 55 means for simultaneously moving said casing, said auger and said power means forwardly, said manually operated means being 60 adapted to simultaneously move said casing, said auger and said power means rearwardly.

HENRY M. WATCHORN.
